[57] CLAIM

The ornamental design for a reel support article, as shown and described.

DESCRIPTION

FIG. 1 is a perspective view of a reel support article, showing the preferred embodiment of the new design.

FIG. 2 is a front elevation view of the reel support article of FIG. 1, the rear being a mirror image of the front.

FIG. 3 is a top plan view of the reel support article of FIG. 1.

FIG. 4 is a bottom plan view of the reel support article of FIG. 1.

FIG. 5 is a right side elevation view of the reel support article of FIG. 1, the left side being a mirror image of the right side; and,

FIG. 6 is a reduced scale, environmental perspective view with the broken line showing of an elongated shaft and second reel support being for illustrative purposes only and forming no part of the claimed design.
